REFRIGERATOR AND BOXCAR DOOR CONSTRUCTION

Luke Scrivanich, Lyndhurst, N. J.

Application August 10, 1936, Serial No. 95,241

8 Claims. (Cl. 20—23)

This invention relates to certain new and useful improvements in refrigerator and box car door constructions.

The primary object of the invention is to provide a door for refrigerator or box cars of the type that sets into a door opening in the side wall of the car and is adapted to be bodily displaced relative to the opening and slid longitudinally of the car laterally of the opening for exposing the latter. In car door constructions of such character, it is known to mount the sliding door on guide tracks with link devices permitting pivotal movements of the door into and out of a door opening, but in such devices, no provision is made for holding the door against movement relative to the car when the same is in a partially opened or closed condition.

It is therefore a further specific object of the invention to provide a latch device for holding the door of a refrigerator or box car in a locked position and restrained by movement when the door is shifted to an open position to prevent injury to the door and car construction and also injury to operators or laborers working about the car.

A still further object of the invention is to provide a novel form of lock device for holding the door in closed position within the door opening.

It is a further object of the invention to provide a novel form of skid plate for association with the sill of the door opening to facilitate loading and unloading of the refrigerator or box car.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a fragmentary side elevational view of a refrigerator or box car with the improved door construction with the door illustrated in its open position and slid laterally of the door opening;

Figure 2 is a vertical detail sectional view through the car wall and door with the latter in closed position and further illustrated by dotted lines in its shifted position in a plane parallel with the side wall of the car;

Figure 3 is a vertical longitudinal sectional view through the bottom guide track for the door showing the roller mounting for the sliding channel section of the lower guide track and the latch device for holding the channel member and door carried thereby against movement;

Figure 4 is a detail sectional view taken on line 4—4 of Figure 3, showing the latch device carried by the sliding channel of the lower guide track engaged with a stationary keeper rail on the side wall of the car;

Figure 5 is a detail sectional view taken on line 5—5 of Figure 3;

Figure 6 is a fragmentary bottom plan view of the keeper rail for the latch device showing the spaced openings or recesses therein to receive the latch device;

Figure 7 is a fragmentary elevational view showing the door in closed position and the lock device for the door;

Figure 8 is a detail sectional view taken on line 8—8 of Figure 7;

Figure 9 is a detail sectional view taken on line 9—9 of Figure 8;

Figure 10 is a detail sectional view taken on line 10—10 of Figure 1, showing the covered sockets in the door sill for attaching one end of a skid plate for loading and unloading;

Figure 11 is a detail sectional view taken on line 11—11 of Figure 10; and

Figure 12 is a detail sectional view showing the skid plate anchored at one end in the door sill with the other end thereof engaged with a loading platform or pier.

Referring more in detail to the accompanying drawings, the reference character 15 designates in general a refrigerator or box car having a side door opening 16 therein that is adapted to be closed by a door 17 that is illustrated in Figure 1 in an open position laterally of the door opening 16 and in a plane offset from and parallel to the adjacent side wall of the car 15. The door 17 is guided in its movement by means of upper and lower guide rails or tracks 18 and 19 respectively.

As shown more clearly in Figure 2, the door opening 16 is bordered by inclined walls 20 including the sill 21 and an abutment wall 22, the door 17 being of double walled construction with the edges thereof inclined as at 23 for engaging the inclined walls 20 and sill 21, the inner side of the door 17 being marginally reduced or of stepped formation to provide the shoulder 24 facing the shoulder 22 and the extension 25 lying within the inner side of the door opening 16. A weather strip or sealing gasket 26 is cooperatively carried by the shoulders 22 and 24 to provide an effective seal for the door.

The mounting of the door 17 upon the upper and lower guide tracks 18 and 19 is shown more clearly in Figures 1 and 2 and includes a pair of vertical bars 27 at the outer side of the door 17

respectively adjacent opposite vertical side edges and an intermediate bar 28, the bars 27 and 28 being journalled adjacent their upper and lower ends in bearing straps 29 carried by the door 17. 5 The upper guide rail 17 comprises a longitudinally extending channel member 30 anchored as at 31 to the side wall of the car 15 above the door opening 16, the upper ends of the bars 27 and 28 each having a link 32 pivoted at one end thereto 10 while the other end of the link 32 carries an up-standing pin 33 upon which a horizontal roller 34 is journalled, the pin and roller extending into the channel guide 30 as shown in Figure 2.

The lower guide rail 19 and the mounting 15 therefor includes angle brackets 35 secured to the side wall of the car 15 below the door opening, the angle brackets 35 having the vertical leg of a T-iron 36 anchored thereto with the cross head of the T-iron horizontally disposed as shown 20 in Figures 2 and 4. A channel member 37 carrying spaced bearing rollers 38 internally thereof is mounted upon the T-iron rail 36, the side legs of the channel member 37 having interlocking engagement with the T-rail with the bearing 25 rollers 38 riding upon the upper horizontal cross head of the T-rail as illustrated. As shown in Figures 1 to 3, bearing blocks 39 for association with the lower ends of the bars 27 and 28 are anchored to the upper closed side of the channel 30 member 37, a link 40 being pivoted at one end to each of the bars 27 and 28, the other end of the link 40 carrying a depending pin 41 received in the bearing block 39 with the adjacent end of the link spaced from the bearing block by the 35 collar 42 surrounding the pin 41 and resting upon the upper end of the bearing block as shown in Figure 3.

The door 17 is carried by and movable with channel members 37 and when the door is in 40 open position, means is associated therewith for holding the same against accidental movement and as shown more clearly in Figures 1 to 6, an angle bar 43 is anchored to the side wall of the car 15 directly above the channel member 45 17 and the under side of the angle bar 43 is longitudinally grooved as at 44 and into which groove an upstanding rib 45 carried by the member 37 extends for further guiding the channel member 37 in its sliding movements on the T- 50 rail 36. The bottom wall of the groove 44 in the angle member 43 is provided with a plurality of spaced sockets 46, the socketed angle member 43 constituting a keeper for a latch device carried by the channel member 37 upon which the door 17 is supported. The latch device includes a lever 47 pivoted as at 48 in the side walls of a slotted opening 49 in the top wall of the channel member 37, the lower end of the lever 47 that extends into the channel member 37 carrying 60 an upstanding pin 50 that is pivoted thereto as at 51, the pin 50 projecting upwardly through an opening in the guide rib 45 to enter a selected socket 46 in the lower side of the angle member 43. An operating handle 52 for the lever 47 is 65 carried by the upper end of the lever above the channel member 37 as shown in Figures 1 and 3 and said lever 47 is tensioned by the spring 53 for normally holding the latch pin 50 at its limit of upward movement and engaged in a socket 46.

70 Means is provided for moving the door 17 into and out of the door opening 16 and as shown in Figures 1 and 7 to 9, the intermediate bar 28 carried by the door 17 has an operating handle 54 of channel formation to be received on the bar 75 28 and pivoted thereto as at 55 adjacent the

lower end of said bar, the lower end of the handle 54 being offset to provide a hand grip 56. When the door 17 is to be moved into and out of the door opening 16, the handle 54 is moved on its pivotal connection 55 to a substantially horizontal position and the same is then moved in the desired horizontal direction for rotating the several bars 27 and 28 to cause the door 17 to swing on the link connections 32 and 40. When the door is in closed position, the hand grip 56 is moved into engagement with a keeper comprising a base plate 57 secured to the side wall of the car 15 adjacent a side of the door opening 16 as shown in Figure 1, the base plate 57 having an angle member 58 secured thereto and a co-acting lever 59 providing a keeper opening 60 for the reception of the hand grip 56 upon the handle 54. The angle member 58 and lever 59 are provided with registering openings 61 as shown in Figure 9 for the reception of the shackle of a padlock or similar device for retaining the lever 59 against movements relative to the angle member 58 with the hand grip 56 retained in the pocket 60 and the door 17 locked against opening movement.

As shown in Figures 10 to 12, the door sill 21 is constructed for the mounting of one end of a loading and unloading skid plate 62 having the outer end thereof resting upon a loading platform or pier 63. The door sill 21 is provided with a series of aligned recesses 64, preferably four in number, with a cover plate 65 extending over one half of each end of a recess 64 with a sliding block 66 in each recess adapted to be moved as shown in Figure 11 to close the upper end of the recess when the same is out of use. The skid plate 62 is of a width approximately three-fifths of the width of the door opening 16 and said skid plate carries a pair of blocks 67 at its underside adjacent one end to rest upon the sill 21 with a depending rib 68 on each block receivable in a recess 64 as shown in Figure 12. The skid plate 62 may be shifted laterally of the door opening 16 for the mounting of the ribs 68 in recesses 64 in the event that the door opening 16 is not directly aligned with the loading platform or pier 63.

From the above detailed description of the invention, it is believed that the construction and operation thereof will at once be apparent, it being noted that the mechanism shown in detail in Figures 3 to 5 securely holds the door 17 against movement when in open position, the latch pin 50 being selectively receivable in the socket 46 whereby the door may be anchored in different positions relative to the door opening 16. With the door in open position, the same is restrained from movement should the car suddenly move and it has frequently occurred by the use of doors of the general type disclosed herein that 55 trainmen have been seriously injured by the sudden closing of the door.

While there is herein shown and described the preferred embodiment of the invention, it is nevertheless to be understood that minor changes 60 may be made therein without departing from the spirit and scope of the invention as claimed.

I claim:

1. In a refrigerator and box car door construction, a car body having a door opening, a door for closing said opening, longitudinally extending upper and lower guide tracks, means connecting the door to the tracks and constructed and arranged whereby the door may swing outwardly of the door opening and slide along the tracks,

and means for holding the door against movement when in open position including cooperating latch mechanism carried by the door and car.

2. In a refrigerator and box car door construction, a car body having a door opening, a door for closing said opening, longitudinally extending upper and lower guide tracks, means connecting the door to the tracks and constructed and arranged whereby the door may swing outwardly of the door opening and slide along the tracks, means for holding the door against movement when in open position including a socketed bar carried by the car, and a tensioned latch pin movable with the door for selective reception in bar sockets.

3. In a refrigerator and box car door construction, a car body having a door opening, a door for closing said opening, longitudinally extending upper and lower guide tracks, means connecting the door to the tracks and constructed and arranged whereby the door may swing outwardly of the door opening and slide along the tracks, means for holding the door against movement when in open position including a socketed bar carried by the car, a channel member movable over the lower track and supporting the door, and a tensioned latch pin carried by the channel member for selective reception in the bar sockets.

4. In a refrigerator and box car door construction, a car body having a door opening, a door for closing said opening, longitudinally extending upper and lower guide tracks, means connecting the door to the tracks and constructed and arranged whereby the door may swing outwardly of the door opening and slide along the tracks, means for holding the door against movement when in open position including a socketed bar carried by the car, a channel member movable over the lower track and supporting the door, the upper wall of the channel member having an opening therein, a lever pivotally mounted in the side walls of the opening, an upstanding latch pin carried by the lower end of the lever, tension means associated with the lever for moving the latch pin upwardly into a socket in the bar and an operating handle carried by the upper end of the lever above the channel member.

5. In a refrigerator and box car door construction, a car body having a door opening, a door for closing said opening, longitudinally extending upper and lower guide tracks, means connecting the door to the tracks and constructed and arranged whereby the door may swing outwardly of the door opening and slide along the tracks, means for holding the door against movement when in open position including a socketed bar carried by the car, a channel member movable over the lower track and supporting the door, the upper wall of the channel member having an opening therein, a lever pivotally mounted in the side walls of the opening, an upstanding latch pin carried by the lower end of the lever, tension means associated with the lever for moving the latch pin upwardly into a socket in the

bar and an operating handle carried by the upper end of the lever above the channel member and anti-friction wheels.

6. In a refrigerator and box car door construction, a car body having a door opening, a door for closing said opening, longitudinally extending upper and lower guide tracks, means connecting the door to the tracks and constructed and arranged whereby the door may swing outwardly of the door opening and slide along the tracks, means for holding the door against movement when in open position including a socketed bar carried by the car, a channel member movable over the lower track and supporting the door, a tensioned latch pin carried by the channel member for selective reception in the bar sockets, the connecting means between the door and tracks including vertical bars journaled at their ends on the outer side of the door, movable bearings on the tracks, link connections between the ends of the bars and the bearings, a lever attached to one bar for simultaneous operation of the door bars for moving the door on the links to open and close the same, and a keeper on the car body for the lever for locking the door in closed position.

7. In a refrigerator and box car door construction, a car body having a door opening, a door for closing said opening, longitudinally extending upper and lower guide tracks, means connecting the door to the tracks and constructed and arranged whereby the door may swing outwardly of the door opening and slide along the tracks, means for holding the door against movement when in open position, the sill of the door opening having a series of aligned recesses therein, slideable closures for the recesses and a skid plate for loading and unloading the car having blocks on the lower side adjacent one end for selective reception in the recesses, said skid plate being of less width than the door opening whereby the same may be laterally shifted relative to the opening for the support of the outer end thereof on a loading platform or the like.

8. In a refrigerator and box car door construction, a car body having a door opening, a door for closing said opening, longitudinally extending upper and lower guide tracks, means connecting the door to the tracks and constructed and arranged whereby the door may swing outwardly of the door opening and slide along the tracks, means for holding the door against movement when in open position including cooperating latch mechanism carried by the door and car, the sill of the door opening having a series of aligned recesses therein, slideable closures for the recesses and a skid plate for loading and unloading the car having blocks on the lower side adjacent one end for selective reception in the recesses, said skid plate being of less width than the door opening whereby the same may be laterally shifted relative to the opening for the support of the outer end thereof on a loading platform or the like.

LUKE SCRIVANICH.
